(57) **CLAIM**

The ornamental design for a display screen or portion thereof
with graphical user interface, as shown and described.

DESCRIPTION

FIG. 1 is a front view of a display screen or portion thereof
with graphical user interface showing our new design, in
which broken lines are provided for illustrative purposes; and
FIG. 2 is a front view of the graphical user interface of FIG. 1,
in which a device in broken lines is provided to illustrate an
example environment; and,
FIG. 3 is a front view of the graphical user interface of FIG. 1.
The broken line showing of the device, and the symbol and
other images is included for the purpose of illustrating envi-
ronmental structure and portions of the article, respectively,
and form no part of the claimed design. The size and scale of
the graphical user interface of FIGS. 1 and 2 are for illustra-
tive purposes and forms no part of the claimed design.
